N. S. Vedder of Troy, N.Y.
Letters Patent No. 519 Dated Nov 2nd 1852

The schedule referred to in these Letters Patent and making part of the same

To all whom it may concern:

Be it known that I, N. S. Vedder, of Troy, in the County of Rensselaer, and State of New York, have invented or produced a new and original design of Cook Stove which I call the "Braiter Oak." I do hereby declare that the following is a full, clear and exact description of the same, reference being had to the annexed isometrical perspective drawing making a part of this specification.

The ornamental design of my Cook Stove consists in the arrangement of oak leaves (a, a, 1) on the panels of the front doors (c, c) and raised panel A, the oak leaf (d) on the panel of the fire door

Des. 519

2

B, also on the small oven door C, the large oven door D is ornamented on the panel with the oak branch, leaves, and acorns (e), and also in the combination of the mouldings (f, f) around the top plate E, hearth F, jamb G, and doors, panels &c. The leg H, is ornamented with the oak branch, leaves and acorns (h).

Having thus described my design of cook stove, what I claim as new and desire to secure by letters patent, is the ornamental design and configuration of cook stove plates, such as herein described, and represented in the annexed drawing.
